TATTING SHUTTLE

Consuelo G. Cisneros, Hollywood, Calif.

Application April 15, 1947, Serial No. 741,546

3 Claims. (Cl. 87—59)

1

This invention relates to tatting shuttles. It is an object of the present invention to provide a tatting shuttle on which a spool of tatting thread can be bodily placed on the shuttle when the two parts of the shuttle have been separated from one another and the spool fitted over the projection on the one part whereby to eliminate the necessity of having to wind thread upon a tatting shuttle thereby wasting time.

Other objects of the present invention are to provide a tatting shuttle wherein there will be little breakage of thread as the thread is placed on the shuttle by a spool wherein injury to the fingers will not be so frequent as the thread does not have to be wound upon the shuttle and wherein a quick change of colors can be made whereby eliminating the necessity for having separate shuttles with different color threads thereon.

Other objects of the present invention are to provide a tatting shuttle which can receive a spool of the thread, which is of simple construction, inexpensive to manufacture and efficient in operation.

For other objects and for a better understanding of the invention, reference may be had to the following detailed description taken in connection with the accompanying drawing, in which

Fig. 1 is a side elevational view of the tatting shuttle.

Fig. 2 is a top plan view of the tatting shuttle.

Fig. 3 is a longitudinal cross-sectional view of the shuttle taken on line 3—3 of Fig. 2.

Fig. 4 is a transverse cross-sectional view taken on line 4—4 of Fig. 2.

Fig. 5 is a transverse cross-sectional view taken on line 5—5 of Fig. 1.

Fig. 6 is a transverse cross-sectional view taken on line 6—6 of Fig. 1.

Referring now to the figures, 10 represents a bottom part of the tatting shuttle to which there is connected to the interior thereof an inwardly extending sleeve 11 having slits 12 extending from the upper edge of the same and into holes 13 of different size to accommodate different size tatting thread.

Extending upwardly from the center of the sleeve 11 and fixed to the part 10 is a central internally threaded sleeve portion 14 adapted to receive a threaded connecting screw 15 having a pivoted handle ring or loop 16 thereon. With the screw 15 removed a spool of thread 17 can be slid downwardly over the sleeve portion 14 and into the sleeve 11. This spool 17 can retain thread of any color or size and the end of the thread is extended through a slit 12 and hole 13

2

and outwardly over the end of the part 10. The spool can rotate so that the thread can be fed from the shuttle.

Adapted to fit over the part 10 is a part 21 forming the opposite side of the shuttle and having an extended portion 22 over which the thread passes. Screw 15 is contained on the part 21 and its handle 16 lies within a depression or recess 23 in the top of the part 21. When the screw is in place as shown in Fig. 3, part 21 is secured to the part 10.

On the inner face of the part 21 is a depending portion 24 adapted to engage with the outer end of the sleeve 11 to retain the part 21 on the part 10 in the proper spaced relationship to permit the rotation of the spool on the sleeve 14. The loop 16 will bear upon the surface of the depressed portion 23 to fix the depending portion 24 upon the outer end of the sleeve 11.

At the opposite sides of the part 21 are dependent exterior portions 27.

After the thread has been used up or should another color of thread be desired, the screw 15 will be loosened from the sleeve 14 and the part 21 separated from the part 10. Thereafter the old spool can be removed from the part 10 and the new spool reinserted. By placing the parts back together again the shuttle is again ready for use.

The sleeve portion 11 is formed of two parts, each of which have longitudinally extending side flanges 29 with the flanges of one part engaging with the flanges of the other part.

While various changes may be made in the detail construction, it shall be understood that such changes shall be within the spirit and scope of the present invention as defined by the appended claims.

40 I claim:

1. A tatting shuttle comprising two separable parts, a sleeve formation on one part adapted to receive a spool of thread when the other part has been separated therefrom, said sleeve portion 45 having an opening through which thread may be extended, and means for securing the other part of the shuttle to the one part to retain the spool in place therewithin, said means including a threaded connecting screw secured to one of said 50 separable parts, an internally screw-threaded receptor member secured to the other of said separable parts, said connecting screw being adapted to seat in said internally screw-threaded receptor member, and cooperating stop means attached to each of said separable parts to hold the 55

parts so as to permit said spool to turn freely when secured in place in said sleeve.

2. A tatting shuttle comprising two separable parts, a sleeve formation on one part adapted to receive a spool of thread when the other part has been separated therefrom, said sleeve portion having an opening through which thread may be extended, and means for retaining the separable parts together, said means including a sleeve portion on the one part having internal threads, a screw connected with the other part and having a handle portion exteriorly thereof adapted to be turned and engaged with the threads of the sleeve of the one part, and stop means to hold the parts so that said spool may turn freely when in place in said shuttle, said stop means including a depending portion on one of said separable parts which engages said longitudinally extending flange portion of said sleeve portion.

3. A tatting shuttle comprising two separable parts, a sleeve portion on one part, said sleeve being formed of two parts, secured together at longitudinally extending side flanges, said sleeve being adapted to receive a spool of thread when the other part has been separated therefrom, said sleeve having an opening through which thread may be extended, means for retaining the separ-

able parts together, said means including a sleeve portion on the one part having internal threads, a screw connected with the other part and having a handle portion exteriorly thereof adapted to be turned and engaged with the threads of the sleeve of the one part, and stop means to hold the parts so that said spool may turn freely when in place in said shuttle, said stop means including a depending portion on one of said separable parts which engages said longitudinally extending flange portion of said sleeve portion.
